CLAIM

The ornamental design for a cosmetic applicator, as shown and described.

DESCRIPTION

FIG. 1 is a perspective view of a cosmetic applicator; FIG. 2 is a top plan view of the cosmetic applicator of FIG. 1;

FIG. 3 is a front view of the cosmetic applicator of FIG. 1; FIG. 4 is a bottom plan view of the cosmetic applicator of FIG. 1; and,

FIG. 5 is a side view of the cosmetic applicator of FIG. 1 as the left side view and the right side view are the same.

The broken lines in the drawings depict portions of the cosmetic applicator that form no part of the claimed design.

1 Claim, 5 Drawing Sheets
